UNITED STATES PATENT OFFICE.

JACOB SCOTT FLEGAL, OF CLEARFIELD, PENNSYLVANIA.

TIE AND RAIL FASTENER.

SPECIFICATION forming part of Letters Patent No. 594,828, dated November 30, 1897.

Application filed May 6, 1897. Serial No. 635,382. (No model.)

To all whom it may concern:

Be it known that I, JACOB SCOTT FLEGAL, a citizen of the United States, residing at Clearfield, in the county of Clearfield and State of Pennsylvania, have invented certain new and useful Improvements in Tie and Rail Fasteners; and I do declare the following to be a full, clear, and exact description of the invention, such as will enable others skilled in the art to which it appertains to make and use the same.

My invention has relation to a combination tie and rail fastener, and the object is to provide a simple, durable, and inexpensive tie which may be manufactured at a small cost.

With this object in view the invention consists of certain features of construction and combination of parts, which will be herein-after more fully described and claimed.

20 In the accompanying drawings, Figure 1 is a plan view of my improved tie and rail fastener. Fig. 2 is a longitudinal sectional view through one end of the same, and Fig. 3 is a cross-sectional view through said end.

25 In the drawings, 1 denotes the base of a metallic tie. 2 denotes metallic blocks at the ends of the tie, and these blocks are provided with grooves 3 in their sides and have pins 4, which project downwardly through holes 5 in the ties. Bolts 6 are used for clamping the blocks to the ties.

7 denotes a rail chair or support, which is provided with lateral flanges 8, that take into the longitudinal grooves in the sides of

the blocks. This chair is held in its desired 35 position by means of a pin 9, which projects into a hole or socket 10, formed in the blocks.

11 denotes clamps which are bolted to the chair 7 and which are adapted to clamp the base of the rail to the chair. These bolts 40 have nuts 12, which are securely held on the bolts by keys 13, fitting in the longitudinal grooves 14, cut in the thread of the bolts.

From the foregoing description, taken in connection with the accompanying drawings, 45 the construction and advantages of a tie thus described will be apparent without further explanation.

Having thus fully described my invention, what I claim as new, and desire to secure by 50 Letters Patent of the United States, is—

The combination of a metallic tie having holes near its ends, blocks having pins at their inner ends which project through the holes in the ties, bolts for securing the outer 55 ends of the blocks to the ties, said blocks being provided with longitudinal grooves in their sides; a chair having side flanges adapted to engage said grooves; a stop-pin for holding the chair in position on said blocks, and 60 clamps bolted to said chair, substantially as set forth.

In testimony whereof I hereunto affix my signature in presence of two witnesses.

JACOB SCOTT FLEGAL.
